UNITED STATES PATENT OFFICE.

HARRY O. RUGH, OF CHICAGO, ILLINOIS, ASSIGNOR TO WESTERN TELEGRAPH COMPANY, OF CHICAGO, ILLINOIS, A CORPORATION OF SOUTH DAKOTA.

TELEGRAPHY.

SPECIFICATION forming part of Letters Patent No. 757,505, dated April 19, 1904.

Application filed August 31, 1903. Serial No. 171,400. (No model.)

To all whom it may concern:

Be it known that I, HARRY O. RUGH, a citizen of the United States, residing at Chicago, in the county of Cook and State of Illinois, 5 have invented a certain new and useful Improvement in Telegraphy, of which the following is a full, clear, concise, and exact description, reference being had to the accompanying drawings, forming a part of this 10 specification.

My invention relates to telegraphy, and has for its object the provision of an improved system and apparatus whereby wave-form current as alternating current of suitably 15 high frequency may be employed in effecting telegraphic signals. By means of my invention the same telegraphic circuit may be simultaneously employed for both wave-form and direct telegraphic currents. To this end 20 I have devised apparatus at the stations employing the instruments to be operated by wave-form current that will effectively respond to the wave-form current at the receiving-stations and which will also be operated 25 at the sending-station without unduly weakening the current, the system enabling the substantially uniform operation of the sounder at the receiving and sending stations.

My invention will be fully pointed out in 30 the following specification and claims and illustrated in the accompanying drawings, in which—

Figure 1 illustrates the preferred embodiment of the invention. Fig. 2 is a view in 35 elevation of the sounder.

Like parts are indicated by similar characters of reference in both views.

I have indicated a transmission-line 1, common to a plurality of telegraphic stations 2, 40 3, 4, 5, and 6. It is understood that the number of each kind of stations may be varied. At stations 2 and 6 are indicated ordinary telegraphic outfits, each including a line-relay 7, normally energized by a battery 8, a sending- 45 key 9, and a sounder 10, whose magnet is included in a local circuit. Additional impedance 11 may be included in the line if said line-relays do not offer enough to prevent undue leakage of wave-form current.

I have indicated the apparatus at stations 50 3, 4, and 5 in grounded conductors 12, each containing a condenser 13. At each of these stations there is a line-relay 14, each preferably including a permanently-magnetized core 15, whose winding may be, say, of one hundred ohms resistance and subject at receiving-stations to the wave-form current impressed upon the line at a sending-station. Each relay includes a vibratory contact element, desirably in the form of a soft-iron diaphragm 60 16, and a movable or traveling contact element 17 resting against the same. The contact 17 is preferably mounted upon a pivoted arm 18 and is given physical inertia by having a weight 19 added to the arm. Any of the current caused by the battery 8 that may find path through the condensers 12 to the relays 14 will fail to cause effective operation of said 65 relays, because the contact 20 is maintained in engagement with the diaphragm not only by 70 reason of the weighted arm, but also by the adjusting-spring 20, that serves to regulate the degree of pressure of the contact against the diaphragm. Wave-form current of sufficiently high frequency, however, will cause 75 separation between the vibratory and traveling contact elements.

At each station there is a sounder 21 contained in a local circuit including the contacts 16 and 17 and a battery 22. Whenever wave-form telegraphic current is impressed upon the line-relays at receiving-stations, the contacts 16 and 17 are separated. The preferred source of wave-form current is an alternating-current generator 22, one generator being indicated at each of the stations 3, 4, and 5. It is of course only necessary to have wires carrying the wave-form current present at each station to act as a supply irrespective of the location of the generator supplying said wires. 85

A sending-key or switching mechanism 23 is located at each of the stations 3, 4, and 5, whose normal contact normally completes the relay-circuit to ground, the ground connection being by way of said key, which is preferably 90 constantly grounded. The alternate contact of said key constitutes a terminal of the supply of wave-form current. When said key is 95

depressed, the magnet of the relay 14 is cut out of circuit. In order that the wave-form current impressed upon the line at a sending-station may operate the sounder to the satisfaction of the sender, I have herein provided an electromagnet 24 at each station that is included in circuit with the source of wave-form current at a sending-station. This electromagnet when energized by outgoing wave-form current attracts its armature away from the normal contact 25 to open the sounder-circuit that also contains said armature with its contact, whereby the operator gets his own "sending." In order that a sound occasioned by the release of the sounder-armature may be totally distinct from that occasioned by its attraction, I provide a sound-dampener 26, that is engaged by the armature-screw 27 upon the attraction of said armature.

It is obvious that changes may be made in the embodiment of the invention herein shown without departing from the spirit of the invention.

Having thus described my invention, I claim as new, and desire to secure by Letters Patent, the following:

1. A system of telegraphy comprising a transmission-line uniting a plurality of telegraph-stations; a supply of wave-form current at each station; a sending-key or switching mechanism at each station; a line-relay at each station comprising a permanent magnet as a core for the helix of the relay, a vibratory contact element actuated by the magnet of the relay, and a traveling contact element possessing inertia and normally resting against said vibratory contact element but separable therefrom through the agency of wave-form current impressed upon the relay; a telegraphic sounder at each station, and a circuit at each station including said sounder and the contacts of the relay, substantially as described.

2. A system of telegraphy comprising a transmission-line uniting a plurality of telegraph-stations; a supply of wave-form current at each station; a line-relay at each station comprising a permanent magnet as a core for the helix of the relay, a vibratory contact element actuated by the magnet of the relay, and a traveling contact element possessing inertia and normally resting against said vibratory contact element but separable therefrom through the agency of wave-form current impressed upon the relay; a telegraphic sounder at each station; a circuit at each station controlling the sounder thereat and normally closed through the contacts of the relay, a sending-key or switching mechanism at each station, and means at each station controlled by the sending-key or switching mechanism thereat and operating independently of the line-relay magnet for effecting operation of the sounder at a sending-station, substantially as described.

3. A system of telegraphy comprising a

transmission-line uniting a plurality of telegraph-stations; a supply of wave-form current at each station; a sending-key or switching mechanism at each station; a line-relay at each station comprising a permanent magnet as a core for the helix of the relay, a vibratory contact element actuated by the magnet of the relay, and a traveling contact element possessing inertia and normally resting against said vibratory contact element but separable therefrom through the agency of wave-form current impressed upon the relay; a telegraphic sounder at each station; a circuit at each station controlling the sounder thereat and normally closed through the contacts of the relay, an electromagnet at each station having circuit connections controlled by the sending-key or switching mechanism thereat and operating independently of the line-relay magnet for effecting operation of the sounder at a sending-station, substantially as described.

4. A system of telegraphy comprising a transmission-line uniting a plurality of telegraph-stations; a supply of wave-form current at each station; a line-relay at each station comprising a permanent magnet as a core for the helix of the relay, a vibratory contact element actuated by the magnet of the relay, and a traveling contact element possessing inertia and normally resting against said vibratory contact element but separable therefrom through the agency of wave-form current impressed upon the relay; a telegraphic sounder at each station; a circuit at each station containing said sounder and the contacts of said relay; a sending-key or switching mechanism at each station, an electromagnet controlling connections of said sounder to deenergize the same when said electromagnet is energized, said electromagnet being adapted for inclusion in circuit with the source of supply through the agency of said key or switching mechanism, substantially as described.

5. A system of telegraphy comprising a transmission-line uniting a plurality of telegraph-stations; a supply of wave-form current at each station; a line-relay at each station comprising a permanent magnet as a core for the helix of the relay, a vibratory contact element actuated by the magnet of the relay, and a traveling contact element possessing inertia and normally resting against said vibratory contact element but separable therefrom through the agency of wave-form current impressed upon the relay; a telegraphic sounder at each station; a circuit at each station containing said sounder and said contacts, a sending-key or switching mechanism at each station, an electromagnet included by said key or switching mechanism in circuit with the supply of wave-form current at a sending-station and a switch controlled by said electromagnet and normally forming a part of the sounder-circuit and operated upon the energization of the electromagnet by the wave-form current

- to open the sounder-circuit, substantially as described.
6. A system of telegraphy comprising a transmission-line uniting a plurality of telegraph-stations; a supply of wave-form current at each station; a line-relay at each station including a vibratory contact element actuated by the magnet of the relay, and a traveling contact element possessing inertia and normally resting against said vibratory contact element but separable therefrom through the agency of wave-form current impressed upon the relay; a telegraphic sounder at each station; a circuit at each station controlling the sounder thereat, and normally closed through the contacts of the relay, a sending-key or switching mechanism, and means at each station controlled by the sending-key or switching mechanism thereat and operating independently of the line-relay magnet for effecting operation of the sounder at a sending-station, substantially as described.
7. A system of telegraphy comprising a transmission-line uniting a plurality of telegraph-stations; a supply of wave-form current at each station; a line-relay at each station including a vibratory contact element actuated by the magnet of the relay, and a traveling contact element possessing inertia and normally resting against said vibratory contact element but separable therefrom through the agency of wave-form current impressed upon the relay; a telegraphic sounder at each station; a circuit at each station controlling the sounder thereat, and normally closed through the contacts of the relay, a sending-key or switching mechanism, an electromagnet at each station having circuit connections controlled by the sending-key or switching mechanism thereat and operating independently of the line-relay magnet for effecting operation of the sounder at a sending-station, substantially as described.
8. A system of telegraphy comprising a transmission-line uniting a plurality of telegraph-stations; a supply of wave-form current at each station; a line-relay at each station including a vibratory contact element actuated by the magnet of the relay, and a traveling contact element possessing inertia and normally resting against said vibratory contact element but separable therefrom through the agency of wave-form current impressed upon the relay; a telegraphic sounder at each station; a circuit at each station containing said sounder and the contacts of the relay, a sending-key or switching mechanism at each station, an electromagnet controlling connections of said sounder to deenergize the same when said electromagnet is energized, said electromagnet being adapted for inclusion in circuit with the source of supply through the agency of said key or switching mechanism, substantially as described.
9. A system of telegraphy comprising a

- transmission-line uniting a plurality of telegraph-stations; a supply of wave-form current at each station; a line-relay at each station including a vibratory contact element actuated by the magnet of the relay, and a traveling contact element possessing inertia and normally resting against said vibratory contact element but separable therefrom through the agency of wave-form current impressed upon the relay; a telegraphic sounder at each station; a circuit at each station containing said sounder and said contacts, a sending-key or switching mechanism at each station, an electromagnet included by said key or switching mechanism in circuit with the supply of wave-form current at a sending-station, and a switch controlled by said electromagnet and normally forming a part of the sounder-circuit and operated upon the energization of the electromagnet by the wave-form current to open the sounder-circuit, substantially as described.
10. A system of telegraphy comprising a transmission-line uniting a plurality of telegraph-stations; a supply of wave-form current at each station; a line-relay at each station comprising a permanent magnet as a core for the helix of the relay, a vibratory contact element actuated by the magnet of the relay, and a traveling contact element possessing inertia and normally resting against the aforesaid contact element but separable therefrom through the agency of wave-form current impressed upon the relay; a circuit at each station including said contact elements, and a telegraph-sounder in said circuit, substantially as described.
11. A system of telegraphy comprising a transmission-line uniting a plurality of telegraph-stations; a supply of wave-form current at each station; a line-relay at each station comprising a permanent magnet as a core for the helix of the relay, a vibratory contact element actuated by the magnet of the relay, and a traveling contact element possessing inertia and normally resting against the aforesaid contact element but separable therefrom through the agency of wave-form current impressed upon the relay; a circuit at each station including said contact elements, and a telegraph-sounder in said circuit, and means whereby the outgoing wave-form current at a sending-station will effect the operation of the telegraphic sounder at said station, substantially as described.
12. A system of telegraphy comprising a transmission-line uniting a plurality of telegraph-stations; a supply of wave-form current at each station; a line-relay at each station comprising a permanent magnet as a core for the helix of the relay, two contact elements normally in engagement controlled by the line-relay; a circuit at each station including said elements, a telegraph-sounder controlled by said circuit, key sending mechanism and an electromagnet controlled by the

key sending mechanism for operating the sounder independently of the line-relay, substantially as described.

13. A system of telegraphy comprising a transmission-line uniting a plurality of telegraph-stations; a supply of wave-form current at each station; a line-relay at each station comprising a permanent magnet as a core for the helix of the relay, two contact elements controlled by the line-relay; a circuit at each station including said elements, a telegraph-sounder controlled by said circuit, key sending mechanism and an electromagnet controlled by the key sending mechanism for operating the sounder independently of the line-relay, substantially as described.

14. A system of telegraphy comprising a transmission-line uniting a plurality of telegraph-stations; a supply of wave-form current at each station, a line-sound-controlling magnet or relay at each station comprising a permanent magnet as a core for the helix of the relay, key sending mechanism, and a relay receiving outgoing current supplementing the line-relay for producing sounds at a sending-station, substantially as described.

In witness whereof I hereunto subscribe my name this 29th day of August, A. D. 1903.
